UNITED STATES PATENT OFFICE.

FREDERICK LOBL, OF MIDDLEBORO, MASSACHUSETTS.

DESIGN FOR AN INHALER.

52,330.

Specification for Design. Patented Aug. 27, 1918.

Application filed April 6, 1918. Serial No. 227,140. Term of patent 14 years.

To all whom it may concern:

Be it known that I, FREDERICK LOBL, a subject of the Emperor of Austria, and a resident of Middleboro, county of Plymouth, and State of Massachusetts, have invented a new, original, and ornamental Design for an Inhaler, of which the following description, in connection with the accompanying drawings, is a specification.

The figure is a perspective view of an inhaler, showing my new design.

I claim:

The ornamental design for an inhaler, as shown.

In testimony whereof, I have signed my name to this specification.

FREDERICK LOBL.
